C. L. BRAUCHER & E. R. JOHNSON.
TIMEKEEPER FOR TELEPHONES.
APPLICATION FILED APR. 14, 1913.

1,113,538.

Patented Oct. 13, 1914.

UNITED STATES PATENT OFFICE.

CLARK L. BRAUCHER AND EDWARD R. JOHNSON, OF CINCINNATI, OHIO.

TIMEKEEPER FOR TELEPHONES.

1,113,538.

Specification of Letters Patent.

Patented Oct 13, 1914.

Application filed April 14, 1913. Serial No. 760,954.

To all whom it may concern:

Be it known that we, CLARK L. BRAUCHER and EDWARD R. JOHNSON, citizens of the United States, and residents of the city of Cincinnati, in the county of Hamilton and State of Ohio, have invented certain new and useful Improvements in Timekeepers for Telephones, of which the following is a full, clear, and exact description, reference 5 being had to the accompanying drawings, forming part of this specification.

For the use of telephones for long distance calls, a flat rate per some fixed interval of time, usually three minutes, is charged by 15 the telephone company, and all minutes or fractions of minutes in excess thereof are charged for at a further rate per minute. In most cases it is very difficult to keep any check on the charges made for these calls, 20 and it is the object of our invention to provide a compact and convenient and inexpensive desk or telephone fixture, readily attached, which will carry a stop watch and a recording pad, and this we accomplish by 25 that certain construction and arrangement of parts to be hereinafter specifically pointed out and claimed.

In the drawings Figure 1 is a front elevation of our device attached to a telephone. 30 Fig. 2 is a bottom elevation of the device with the telephone attachment. Fig. 3 is a perspective view of the same with the stand support attached. Fig. 4 is a similar view of the stand. Fig. 5 is a view of the watch casing. Fig. 6 is a central vertical section, on the line 6, 6, of Fig. 2.

1 is a telephone pedestal of an ordinary telephone instrument having the transmitter 2 and the receiver 3. We provide a metal 40 plate or stamping 4 upon which to mount the parts of our device, at one end of which are located the fastening bolts 5, 5. On the shanks of the bolts is placed a recording pad 6, preferably marked and ruled for convenience in making a memorandum of long 45 distance calls, and the pad held in place by the nuts 7, 7, of the bolts. At the other end of the plate 4 is provided the circular opening 8 for a watch dial. The watch which is 50 preferably a stop watch having a check 9 as well as a stop and return 10, is secured in the following manner. A circular casing 11 of a size adapted to receive the watch and having the apertures 12 and 13 for the 55 check and the stop arbors respectively, is provided. In opposed relation on the sides of the casing are the lugs 14, 14, in which are the slots 15, 15, with large ends adapted to fit over the buttons 33, 33, on the plate 4. This casing can of course be made of one 60 piece of metal, and this is the desired nature of casing, as it is the intention throughout to provide the most durable and inexpensive means that is possible. Its method of use 65 is obvious.

The construction above described covers the features of the device employed in keeping track of long distance telephone calls, i. e. the stop watch for keeping the time and the pad for keeping the memoranda. The 70 balance of the features of the device comprise the several means of attachment, these also being designed for durability, simplicity and cheapness.

On both sides of the plate 4, located on its 75 under surface are the raised strips 16, 16, forming sockets for tongues on the attaching means. These sockets may be, and are, preferably formed by cutting and stamping them from the surface of the plate 4. This 80 is the most inexpensive way, and although it leaves the apertures 17, 17, in the surface of said plate, they are not at all unsightly.

We provide as a means of attachment to a telephone pedestal, the clamping member 85 formed with the two arms 18 and 19, having curved inner surfaces to fit the standard pedestal. At the outer ends of these arms are the depending lugs 20, 20, held together by the bolt 21. The loosening of this bolt 90 allows the arms to swing on each other, and the arms may be adjusted for different sized pedestals by means of this bolt, as is obvious. The arm 19, which is the stationary 95 arm, has the laterally extending portion 22, which extends preferably clear across the plate 4, and is there fastened to the plate by the pin and nut 23. The arm 19 has also the laterally extending tongue 24 which fits under the raised strip 16 aforementioned. A pin and nut 25 are provided on the plate 4, to fasten the arm 18 to the said plate. In setting up and putting into operation this clamp, the stationary arm is inserted in place as described, the movable 100 arm swung on the bolt 21 around the telephone pedestal, fastened to the plate by the nut 25, and then tightened over the pedestal by turning the nut on the bolt 21. The other means of attachment consists in the 105 three sided incline standard 26, having the end portion 27 and the inclined edged side

portions 28, 28. The tongues 29, 29, are provided on the side portions to fit into the sockets formed by the raised strips 16, 16, of the plate 4. We prefer also to provide 5 the hinge connection 30, the knuckles 31, 31 of which are on the end of the plate 4 and on the top of the end portion 27 in order to further secure the incline standard to the plate. By this means, the device may be 10 stood upon a desk or table. If it is desired to fasten it to the wall, the standard 26 may be used and the screws for attachment inserted through the holes 32, located in the end portion of the standard for that purpose.

It will thus be apparent that means are provided whereby the plate upon which are mounted the memorandum pad and the stop watch, can be easily and securely fastened to a telephone instrument, or may be 20 stood upon a flat surface, or fastened to a wall, at will.

The construction of parts is simple and durable and produces a neat and attractive 25 article.

Having thus described our invention, what we claim as new and desire to secure by Letters Patent is:—

1. A plate for mounting a watch having an orifice of a size smaller than the size of a 30 desired time piece, a time piece casing, and means on the under side of the plate for mounting said casing thereon, said plate being of a length sufficient to accommodate a pad of paper for making a record. 35

2. A combination of a plate having a means of supporting the same, said plate having an orifice of a size smaller than the size of a desired time piece, pins on the under side of the plate near said hole, and a 40 casing for a time piece, and means on the casing for detachably mounting the same on the pins, with said plate being of a length sufficient to accommodate a pad of paper for making a record.

CLARK L. BRAUCHER.
EDWARD R. JOHNSON.
